ROCKING JOURNAL CONNECTION

Robert B. Cottrell, Chicago, Ill., assignor to American Steel Foundries, Chicago, Ill., a corporation of New Jersey

Application June 30, 1944, Serial No. 542,971

12 Claims. (Cl. 105—223)

1

My invention relates to railway car trucks and more particularly to a novel journal box mounting for a freight car truck.

The general object of my invention is to design a novel truck wherein the journal boxes of the wheel and axle assemblies are capable of limited relative vertical and horizontal angling with respect to the truck side frames which are interconnected by an intervening bolster in the conventional manner.

My invention is illustrated as applied to a roller bearing journal box to which the invention is especially adapted; however, it will be understood that my novel principle may be applied to other types of boxes if desired.

It will be understood by those skilled in the art that in a freight car truck such as above described, the wheel and axle assemblies frequently assume various angularities with respect to the side frames as the truck passes over curved or uneven sections of track, and it is the primary object of my invention to accommodate such angularities to a limited extent.

A specific object of my invention is to provide a novel combination of abutment surfaces on the side frame pedestal jaws and the journal box flanges which embrace such jaws; whereby extreme vertical and horizontal angling of the journal box relative to the side frame is limited by engagement of certain of said flanges with adjacent surfaces of the pedestal jaws. It will be understood that such extreme vertical and horizontal angling is the result of unusual track conditions and is frequently of such force as would result in damage to the various truck parts. My invention prevents such damage by a novel combination of abutment surfaces on the box and side frame pedestal jaws, as above described.

In the drawings, Figure 1 is a fragmentary side elevation of one end of a railway car truck embodying my invention, the wheel and axle assembly and associated journal box being shown in section along the vertical longitudinal plane indicated by the line 1—1 of Figure 2.

Figure 2 is a fragmentary top plan view of the structure shown in Figure 1, and Figure 3 is a fragmentary end view taken from the right as seen in Figures 1 and 2.

Describing my invention in detail, the side frame comprises tension and compression members 2 and 4 defining a window fragmentarily indicated at 6 and merging at their ends to form an end portion with depending pedestal legs or jaws 8, 8 defining a pedestal opening therebetween for reception of a journal box 10 having

spaced inboard and outboard flanges 12 and 14 at each side thereof embracing the adjacent jaw 8 to afford an interlock therewith. The outer jaw 8 is cored away as at 15 to lighten the structure. It may be noted that the frame tapers in width toward its extremity, as seen in Figure 2, and for this reason, the frame is offset at 16 (Figure 1) so that the inner jaw 8 is of substantially the same dimensions as the outer jaw 10 which, as best seen in the end view of Figure 3, tapers downwardly for a purpose hereinafter particularly described.

The box 10 is formed on the top thereof with two spaced arcuate bearing surfaces 18, 18 curving transversely of the side frame and affording convex seats having abutment at 20, 20 with wear pads or bearing plates 22, 22 secured in any convenient manner, as by welding, to the side frame within the pedestal opening at opposite sides thereof. The journal box 10 is also provided adjacent its inboard and outboard extremities with upstanding lugs 24, 24 presenting arcuate faces 26, 26 adjacent the side frame for cooperation therewith to limit extreme vertical angling of the wheel and axle assembly 28, as hereinafter described, said faces being horizontally arcuate to accommodate horizontal angling of said assembly.

The wheel and axle assembly, which is fragmentarily indicated at 28, comprises a journal end received within the journal box 10 for rotation therewithin, said box being provided with any conventional roller bearing assembly (not shown) within the cavity 30 to afford an antifrictional bearing for the wheel and axle assembly, as will be clearly apparent to those skilled in the art. The outboard end of the journal box is closed by a suitable cover plate 32 secured thereto at 34, 34 (Figure 1) as by bolts (not shown); and an oil plug 36 is screwed into said cover plate and wired thereto as at 38, said plug being readily removable for the purpose of lubricating the bearings within the journal box.

Referring now to Figure 3, it will be understood that under service conditions wherein normal vertical angling occurs between the wheel and axle assembly 28 and the side frame, the journal box 10 and side frame are afforded relative rocking movement at 20, 20 on the surfaces 18, 18. Under unusual conditions wherein extreme vertical angling occurs between the wheel and axle assembly 28 and the side frame, the surface 26 on one of the lugs 24 engages a pad 40 on the adjacent side of the frame to limit this rocking.

movement between the frame and the journal box 10.

As will be seen in Figure 3, each jaw 8 is tapered toward its lower extremity and presents at opposite sides thereof the diagonal converging inboard and outboard plane faces 42 and 44 respectively which are afforded clearance from the adjacent surfaces 46 and 48 of the inboard and outboard journal box flanges 12 and 14 during relative vertical angling between the wheel and axle assembly 28 and the side frame unaccompanied by any horizontal angling therebetween.

When, however, under severe service conditions as, for example, when the truck proceeds around a curve in the track, it will be understood that extreme vertical angling may be accompanied by simultaneous extreme horizontal angling between the side frame and the wheel and axle assembly 28, in which event, one of the surfaces 46 or 48 will abut the associated surface 42 or 44 to limit this extreme horizontal and vertical angling which may occur with great force. In order to accommodate such conditions and to prevent damage to the various truck parts, the surfaces 46 and 48 and the surfaces 42 and 44 are so designed as to insure engagement between one pair of surfaces 42 and 46 or 44 and 48. Thus, it will be noted that said surfaces 42 and 44 converge downwardly, and the surfaces 46 and 48 of each pair of inboard and outboard journal box flanges 12 and 14 converge toward the longitudinal axis or center line of the wheel and axle assembly 28, and these various surfaces are so proportioned that a combination of extreme horizontal and vertical angling of the wheel and axle assembly 28 relative to the side frame results in flat face engagement between one pair of surfaces 42 and 46 or 44 and 48 throughout substantially the entire area thereof and substantially simultaneous line bearing between the diagonally opposite pair of surfaces.

Each jaw 8 is connected to one pair of the inboard and outboard flanges 12 and 14 by means of a bolt and nut assembly 50 secured to said flanges and extending through an enlarged slot or opening 52 (Figure 1, left) in said jaw. It will be understood that the slot 52 is sufficiently large to afford clearance from the bolt and nut assembly 50 during the above-mentioned angling between the wheel and axle assembly and the side frame.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a journal box mounting for a railway car truck, a side frame tapering in width toward the end thereof and formed at said end with spaced depending pedestal jaws each presenting substantially identical plane abutment faces on the inboard and outboard sides thereof converging toward the bottom thereof, a wheel and axle assembly including a journal box received between said jaws and presenting at opposite sides thereof of spaced bearing surfaces arcuately formed transversely of said frame and affording seats respectively for wear plates welded to said frame intermediate said jaws, said box having at each side thereof inboard and outboard flanges embracing the adjacent jaw and normally spaced

therefrom, said flanges presenting inboard and outboard abutment surfaces converging toward the longitudinal axis of said assembly whereby extreme vertical and horizontal angling of said assembly relative to said frame is limited by engagement between one of said surfaces and the adjacent face, and inboard and outboard lugs on said box upstanding therefrom centrally thereof, said lugs presenting horizontally arcuate faces on their adjacent surfaces for abutment with said frame to limit relative vertical angling between said assembly and said frame unaccompanied by relative horizontal angling.

2. In a journal box mounting for a railway car truck, a side frame tapering in width toward the end thereof and formed at said end with spaced depending pedestal jaws, each presenting substantially identical plane abutment faces on the inboard and outboard sides thereof converging toward the bottom thereof, a wheel and axle assembly including a journal box received between said jaws and affording a rockable seat for said frame, said box having at each side thereof inboard and outboard flanges at opposite sides of the adjacent jaws, said flanges presenting respectively inboard and outboard abutment surfaces converging toward the longitudinal axis of said assembly, whereby extreme vertical and horizontal angling of said box relative to said frame is limited by engagement between one of said surfaces and the adjacent face, central inboard and outboard upstanding lugs on said box at opposite sides of said frame for abutment therewith to limit relative vertical angling between the box and the frame unaccompanied by horizontal angling, said lugs being horizontally arcuate on the surfaces thereof adjacent said frame to accommodate said horizontal angling.

3. In a journal box mounting for a railway car truck, a frame member with spaced pedestal jaws, a journal box received therebetween and comprising at each side thereof inboard and outboard flanges with abutment faces on their adjacent sides converging toward the center line of said box, said frame being provided with spaced wear plates welded thereto and seated upon transversely arcuate bearing surfaces atop said box at opposite sides thereof, each of said jaws presenting abutment surfaces on opposite sides thereof converging downwardly, said abutment surfaces and faces being so formed and arranged that upon simultaneous extreme vertical and horizontal angling of said box relative to said frame, the inboard face at one side of said box is in engagement with the adjacent surface, and the outboard face at the opposite side of said box is in engagement with the adjacent surface, one of said engagements being along flat areas, and means interlocking each jaw with the adjacent flanges, said means including a rigid member secured to said last-mentioned flanges and extending through an enlarged opening through said jaw, said rigid member being afforded sufficient clearance from the margins of said opening to accommodate said horizontal and vertical angling.

4. In a journal box mounting for a railway car truck, a frame member with spaced pedestal jaws, a journal box received therebetween and comprising at each side thereof inboard and outboard flanges with abutment faces on their adjacent sides converging toward the center line of said box, said frame being provided with spaced wear plates welded thereto and seated upon transversely arcuate bearing surfaces atop said

box at opposite sides thereof, each of said jaws presenting abutment surfaces on opposite sides thereof converging downwardly, said abutment surfaces and faces being so formed and arranged that upon simultaneous extreme vertical and horizontal angling of said box relative to said frame, the inboard face at one side of said box is in engagement with the adjacent surface, and the outboard face at the opposite side of said box is in engagement with the adjacent surface, one of said engagements being along flat areas, lugs on the top of said box centrally thereof at the inboard and outboard sides of said frame for abutment therewith to limit vertical angling of the box unaccompanied by horizontal angling thereof, said lugs being horizontally arcuate on their adjacent surfaces to accommodate horizontal angling of said box.

5. In a journal box mounting for a railway car truck, a side frame tapering in width toward the end thereof and formed at said end with spaced depending pedestal jaws each presenting substantially identical plane abutment faces on the inboard and outboard sides thereof converging toward the bottom thereof, a wheel and axle assembly including a journal box received between said jaws and presenting at opposite sides thereof spaced bearing surfaces arcuately formed transversely of said frame and affording seats respectively for wear plates welded to said frame intermediate said jaws, said box having at each side thereof inboard and outboard flanges embracing the adjacent jaw and normally spaced therefrom, said flanges presenting inboard and outboard abutment surfaces converging toward the longitudinal axis of said assembly whereby extreme simultaneous vertical and horizontal angling of said assembly relative to said frame is limited by flat face engagement between one of said surfaces and the adjacent face, and a bolt and nut assembly loosely received within an opening in each jaw and rigidly secured to the associated flanges.

6. In a journal box mounting for a railway car truck, a frame member with spaced pedestal jaws, a journal box received therebetween and comprising at each side thereof inboard and outboard flanges at opposite sides of the adjacent jaw and formed with abutment faces on their adjacent sides converging toward the center line of said box, said box affording a rockable seat for said frame, each of said jaws presenting abutment surfaces on opposite sides thereof converging downwardly, said abutment surfaces and abutment faces being so formed and arranged that upon simultaneous extreme vertical and horizontal angling of said box relative to said frame, one of said faces is in flat face engagement with the adjacent surface, lugs on top of said box at the inboard and outboard sides of said frame for abutment therewith to limit vertical angling of the box unaccompanied by horizontal angling thereof, said lugs being horizontally arcuate on their adjacent surfaces to accommodate horizontal angling of said box.

7. In a journal box mounting for a railway car truck, a side frame tapering in width toward the end thereof and formed at said end with spaced depending pedestal jaws, each presenting substantially identical plane abutment faces on the inboard and outboard sides thereof converging toward the bottom thereof, a wheel and axle assembly including a journal box received between

said jaws and affording a rockable seat for said frame, said box having at each side thereof inboard and outboard flanges at opposite sides of the adjacent jaw, said flanges presenting respectively inboard and outboard abutment surfaces converging toward the longitudinal axis of said assembly, whereby extreme simultaneous vertical and horizontal angling of said box relative to said frame is limited by engagement between one of said surfaces and the adjacent face, and a bolt and nut assembly loosely received within an opening through each jaw and connected to the associated flanges.

8. In a journal box mounting for a railway car truck, a side frame tapering in width toward the end thereof and formed at said end with spaced depending pedestal jaws each presenting substantially identical plane abutment faces on the inboard and outboard sides thereof converging toward the bottom thereof, a wheel and axle assembly including a journal box received between said jaws and presenting at opposite sides thereof spaced bearing surfaces arcuately formed transversely of said frame and affording seats respectively for wear plates welded to said frame intermediate said jaws, said box having at each side thereof inboard and outboard flanges embracing the adjacent jaw and normally spaced therefrom, said flanges presenting inboard and outboard abutment surfaces converging toward the longitudinal axis of said assembly whereby extreme simultaneous vertical and horizontal angling of said assembly relative to said frame is limited by flat face engagement between one of said surfaces and the adjacent face.

9. In a journal box mounting for a railway car truck, a frame member with spaced pedestal jaws, a journal box received therebetween and comprising at each side thereof inboard and outboard flanges at opposite sides of the adjacent jaw and formed with abutment faces on their adjacent sides converging toward the center line of said box, said box affording a rockable seat for said frame, each of said jaws presenting abutment surfaces on opposite sides thereof converging downwardly, said abutment surfaces and abutment faces being so formed and arranged that upon simultaneous extreme vertical and horizontal angling of said box relative to said frame, one of said faces is in engagement with the adjacent surface, and a bolt and nut assembly loosely received within a slot in each jaw and secured to the associated flanges.

10. In a journal box mounting for a railway car truck, a side frame tapering in width toward the end thereof and formed at said end with spaced depending pedestal jaws, each presenting substantially identical plane abutment faces on the inboard and outboard sides thereof converging toward the bottom thereof, a wheel and axle assembly including a journal box received between said jaws and affording a rockable seat for said frame, said box having at each side thereof inboard and outboard flanges at opposite sides of the adjacent jaws, said flanges presenting respectively inboard and outboard abutment surfaces converging toward the longitudinal axis of said assembly, whereby extreme simultaneous vertical and horizontal angling of said box relative to said frame is limited by engagement between one of said surfaces and the adjacent face.

11. In a journal box mounting for a railway car truck, a frame member with spaced pedestal jaws, a journal box received therebetween and comprising at each side thereof inboard and out-

board flanges with abutment faces on their adjacent sides converging toward the center line of said box, said frame being provided with spaced wear plates welded thereto and seated upon transversely arcuate bearing surfaces atop said box at opposite sides thereof, each of said jaws presenting abutment surfaces on opposite sides thereof converging downwardly, said abutment surfaces and faces being so formed and arranged that upon simultaneous extreme vertical and horizontal angling of said box relative to said frame, one of said faces at one side of said box is in engagement with the adjacent surface.

12. In a journal box mounting for a railway car truck, a frame member with spaced pedestal jaws, a journal box received therebetween and comprising at each side thereof inboard and outboard flanges at opposite sides of the adjacent jaw and formed with abutment faces on their adjacent sides converging toward the center line of said box, said box affording a rockable seat for said frame, each of said jaws presenting abut-
